GOLF CLUB HEAD SOLE PLATE

Alfred A. Steponaitis, 232 Chipman St.,
Waterbury, Conn.

Filed Oct. 19, 1959, Ser. No. 57,973

Term of patent 14 years

(Cl. D34—5)

The single figure on the drawing is a perspective view of the golf club head sole plate showing my new design.

The essential feature of my design resides in the decorated sole plate as shown in full lines in the drawing. The golf club head is shown in dotted lines to indicate the environmental use thereof.

I claim:

The ornamental design for a golf club head sole plate, as shown and described.
